WHEELBARROW STRUCTURE

Joseph D. Forrer, Jackson, Mich., assignor to
Sheet Aluminum Corporation, Jackson, Mich.,
a corporation of Michigan

Application June 29, 1932, Serial No. 619,832

3 Claims. (Cl. 280—52)

The present invention relates to an improvement in wheelbarrow structure and has particular reference to wheelbarrows of the type shown in application No. 580,792, filed December 14, 1931.

5 In order to reduce the weight of the usual steel wheelbarrow it is necessary to resort to more expensive metals for lightness of structure, for example, aluminum alloys. It is found not to be practical to merely substitute the lighter metal 10 into the usual steel wheelbarrow construction but that it is necessary to reduce the cubic area of metal employed and completely redesign the structure in order to provide the necessary rigidity with a minimum amount of metal.

15 It therefore becomes the primary object of my invention to provide an improved wheelbarrow frame which will permit the employment of light, relatively thin structural members and will at the same time possess all the necessary rigidity.

20 More specifically stated, one of the objects of my invention is to combine the function of frame and legs in one self-contained member thereby reducing the labor of fabrication and at the same time provide a truss construction which produces maximum strength and rigidity with a 25 minimum amount of material.

Another object of my invention is to provide a structure which will enable the wheel to be mounted in the frame with the top thereof located 30 substantially in the plane of the bottom of the tray thus permitting the tray to be supported more directly over the axle of the wheel than is possible in prior wheelbarrow designs.

35 A further object of my invention is to provide a wheelbarrow construction formed entirely from sheet material, preferably of an aluminum alloy, which will weight less than 40 pounds yet possess the capacity, strength and rigidity of a steel construction of more than double the weight.

40 Other objects and advantages of my invention will appear as the description of the invention proceeds. It is to be clearly understood, however, that I do not intend to limit myself to the exact details shown or described but that I intend to 45 include as part of my invention, all such changes and modifications of parts as would occur to those skilled in this art and would fall within the scope of the claims.

45 In the drawing, Fig. 1 is a perspective view of the complete wheelbarrow structure.

Fig. 2 is a plan view of the frame structure with the wheel and tray removed.

50 Fig. 3 is a side elevation of the structure shown in Fig. 2.

With reference to the drawing, my improved wheelbarrow structure, generally designated 1, consists of the usual tray portion 2 supported on and secured to a frame portion generally designated 3 provided with handles 4 and a wheel 5.

As the construction of the frame 3 forms an important part of my invention the same shall now be described in detail: Tray supporting upper truss members 6, preferably of rolled channel, extend the entire length of the frame 3, and are slightly deflected at 7 to properly elevate the handle 4 with respects to the ground and tray. Lower truss members 8, preferably of rolled channel, have their flanges cut at 9 and the adjacent section of the members 8 are bent inwardly to juxtaposition the portions of the flanges contiguous the cut 9 to enable a rivet 10 to be passed therethrough. The sections of the lower truss members 8 are fixedly secured to the top truss members 6 by any well known means, preferably rivets 11 and 12. To increase the rigidity of the truss members 6 and 8, braces 13 are provided directly over the wheel bearing 14 thus to more directly transmit the weight of the load to the axle of the wheel 5. The braces 13 are preferably channel members and are secured within the channels 6 and 8 with the respective flange portions juxtaposed. In the claims the frame constituted by the members 6—7—8 is referred to as a belly truss.

Additional bracing members 15 are provided to increase the rigidity, and cooperate with the braces 13 to distribute the load supported by the handle 4 between the truss members 6 and 8. The braces 15 as illustrated are of L-shape construction having one flange riveted to the outer flange of the members 6 and 8. Lateral rigidity is imparted to the frame structure through the employment of tie rods 16 secured to the inward flanges of the braces 15.

The opposed section of the truss members 6 and 8 are rigidly spaced at the forward end of the frame in a spacing channel member 17. A channel brace 18 may be interposed between the front of the tray 2 and the member 17 to stiffen the tray and support a portion of the load of the tray forward of the axle of the wheel 5.

As shown, the tray 2 is directly supported on the truss members 6 and may be fixedly secured thereto by rivets or the like or detachably secured by bolts. To remove all tendency for the framework to twist when the wheelbarrow is tilted to either side in a heavily loaded condition, tie rods 17 are secured to the truss members 6 adjacent the handles 4 and are secured (not

shown) in the central portion of the frame to the bottom of the tray 2.

An axle 19 is mounted in the bearing 14 and the supported wheel 5, which is preferably provided with a low pressure pneumatic tire, is mounted thereon upon frictionless bearings.

Obviously the members 6 and 8 could be telescoped at their ends to form handle portions, however, I prefer to insert wooden handles within the channels and removably secure them there by bolts.

Although the above described frame structure is especially adapted for fabrication from aluminum alloys, it will be readily apparent that the advantages resulting therefrom will manifest themselves regardless of the material employed.

From the foregoing description it will be apparent to those skilled in the art that I have provided a wheelbarrow frame composed of truss sections which are rigidly braced in all directions. Furthermore, I have provided a relatively light but rigid structure through the construction of the supporting leg directly in the frame as on self-contained member which permits lighter gage material to be the wheel to be mounted in a manner permitting the tray to be supported further front than has been possible herebefore.

Having thus described my invention, what I claim as new and desire to cover by Letters Patent is:

1. A wheelbarrow comprising spaced vertical side frames having tray supporting and leg portions, said side frames being in the form of belly trusses converging toward the front of said wheelbarrow and being spaced to provide clearance for a wheel, the portions of said trusses

constituting the legs diverging upwardly and intersecting the tray supporting portions contiguously with the ends thereof, a wheel supported on the portions of said trusses constituting the legs, handles located at the rear intersection of the tray supporting and leg portions, a tray supported upon said tray supporting portions, and bracing and tying members located in intersecting planes spacing said sections laterally.

2. A wheelbarrow comprising spaced vertical side frames having tray supporting and leg portions, said side frames being in the form of belly trusses converging toward the front and being spaced to provide clearance for a wheel, the portions of said trusses constituting the legs diverging upwardly and intersecting the tray supporting portions contiguously with the ends thereof, a wheel supported upon the portions of said trusses constituting the legs, handles located at the intersection of tray supporting and leg portions, a tray supported upon said tray supporting portions, and means spacing and bracing said trusses.

3. A wheelbarrow comprising spaced vertical side frames having tray supporting and leg portions, said frames being in the form of belly trusses converging toward the front of said wheelbarrow and being spaced to provide clearance for a wheel, the portions of said trusses constituting the legs diverging upwardly and intersecting the tray supporting portions contiguously with the ends thereof, a wheel supported upon the portions of said trusses constituting the legs, handles located at rear intersection of the tray supporting and leg portions, and a tray supported upon said tray supporting portions.
